UNITED STATES PATENT OFFICE.

KARL S. BRECKENRIDGE, OF CHICAGO, ILLINOIS, ASSIGNOR TO AMERICAN CAN COMPANY,
OF NEW YORK, N. Y., A CORPORATION OF NEW JERSEY.

FRICITION-TOP CAN.

No. 878,766.

Specification of Letters Patent.

Patented Feb. 11, 1908.

Application filed March 31, 1906. Serial No. 309,049.

To all whom it may concern:

Be it known that I, KARL S. BRECKENRIDGE, a citizen of the United States, residing in Chicago, in the county of Cook and 5 State of Illinois, have invented a new and useful Improvement in Friction-Top Cans, of which the following is a specification.

My invention relates to improvements in the construction of friction top cans or cans 10 which are adapted to be repeatedly closed by simply pressing what is known as a friction cap or cover into the opening in the can top or head which is surrounded by an annular depending friction seat wall or flange.

Heretofore considerable difficulty has been 15 experienced in the practical use of friction top cans in securing a liquid tight closure, and also from the circumstance that when the can is opened by prying off the friction 20 cap or cover, dust or dirt which may have collected in the annular groove of the can top surrounding the outer edge or rim of the horizontally projecting flange of the cap or cover, or sawdust or other material in which 25 the cans are frequently packed for shipment, collects in such groove or channel, and is liable to fall into the can and get mixed into the paint or other material in the can.

The object of my invention is to provide a 30 simple, strong, efficient and durable construction of friction top can by means of which these difficulties may be practically obviated or overcome.

My invention consists in the means I employ to practically accomplish this object or 35 result. That is to say, it consists in connection with the body of the can, and the customary so-called friction top or upper head therefor, furnished with an annular depending friction seat wall or flange surrounding the opening therein and an outer annular raised rim or flange uniting said top or head to the can body, with an annular depression or channel between such outer raised rim 40 and the inner depending friction seat wall or flange, of a friction cap or cover having the customary annular friction seat wall or flange adapted to fit within the annular friction seat wall or flange of the can top and 45 provided with an outwardly projecting rim or flange extending over the raised outer rim of the can top or head and adapted to engage said outer raised rim of the can top when the friction cap or cover is forced home on the 50 can and thus afford a positive stop or limit

to the extent to which the cap or cover may be forced into the can top. This outwardly projecting flange of the friction cap or cover is furnished with an annular groove or channel which serves to strengthen and stiffen 60 the same. By these means, I am enabled to produce a successful and practical liquid tight closure for friction top cans, as in my can, the friction can or cover has a positive stop to limit the extent to which it can be 65 forced into the friction top or head of the can and thus entirely obviates the prolific cause of leakage in friction top cans due to the cover being driven too far and thus stretching, expanding and cracking or breaking the annular depending friction seat wall or flange of the can top the lower edge of which flange is left plain to give the flange the necessary elasticity and tight grip upon the cover. And at the same time by my in- 70 vention, the annular channel or groove in the can top between its outer rim and its friction seat wall or flange is covered, closed and protected from admission of dust, dirt or sawdust or other material by the out- 75 wardly projecting rim of the cover which extends over and fits snugly down against the outer raised rim of the can top.

In the accompanying drawing forming a part of this specification, Figure 1 is a central vertical sectional view of a friction top can embodying my invention. Fig. 2 is a plan view and Fig. 3 is a detail sectional view of the friction cap or cover.

In the drawing, A represents the can body, B the friction top or upper head, C the bottom head and D the friction cap or cover. The bottom head C is united to the can body A by a folded or other seam c which may be also preferably soldered if desired. The friction top or head B has an outer upwardly projecting flange b and a downwardly projecting flange b' embracing the upper end of the can body and uniting the same therewith, and forming an outer annular raised shoulder or rim b² on the can top. The seam uniting the can top B with the upper end of the can body is preferably also soldered. The annular top or head B is also furnished with a depending annular friction seat wall or flange b³, surrounding the opening B¹ in the can top. The annular can top B also has an annular depression, groove or channel b⁴ between its outer annular raised rim b² and its inner annular shoulder b⁵ at the junction 110

of its depending annular seat wall or flange b^3 , this groove or channel serving to stiffen and strengthen the annular can top.

The friction cap or cover D has the customary friction seat wall or flange d and an outwardly projecting flange d^1 furnished with a fold d^2 at its outer rim or edge, which extends over and is adapted to engage the outer raised annular shoulder or rim b^2 of the annular top B, and thus serve as a stop or limit to the extent to which the friction cap or cover D may be forced into the annular top B. The outwardly projecting flange d is also furnished with an annular depression 15 groove or channel d^3 between its outer annular shoulder or rim d^2 and its inner annular shoulder d^4 which is at the junction of the depending annular friction seat wall or flange d . The inner and outer annular shoulders d^4 and d^2 of the friction cap or cover D are preferably flush with each other so that the pressure of the plunger or tool used in driving or forcing the cap or cover D into the annular top B of the can may come 20 partially upon both these shoulders. As the outwardly projecting flange d^1 of the friction cap or cover D projects over and fits against the outer annular raised shoulder b^2 of the can top B when the cover D is forced home, it thus serves as an absolute and positive 25 stop or limit to the extent to which the cover may be driven into the can top and thus prevents all danger of stretching, breaking or cracking the annular friction seat wall or flange b^3 of the annular top B and at the same time effectually closes and excludes dust, dirt and sawdust from the upper surface of the annular can top. A slight clearance space x may be left between the upper 30 surface of the annular top and the under surface of the flange d^1 of the cover D so that the contacting surfaces between the annular top and the cover will be only at the friction seat walls or flanges b^3 and d and at the annular 35 stop shoulders b^2 and d^2 .

I claim:

1. In a friction top can, the combination with an annular top B having an outer annular raised shoulder, and an inner annular depending friction seat wall surrounding the opening in the annular top of the can, and having an annular channel within said outer annular shoulder; of a friction cover having an annular friction seat wall fitting within 40 the annular friction seat wall of the can top and provided with an outwardly projecting flange having an outer rim extending over and fitting against the said outer annular raised shoulder on the can top to serve as a 45 stop and limit the extent to which the said friction cover may be forced into the annular top of the can and to exclude dirt or other materials from the upper surface of the can top, said annular top and cover contacting only at their interengaging friction seat walls

and at their outer annular shoulders, substantially as specified.

2. In a friction top can, the combination with an annular top B having an outer annular raised shoulder, and an inner annular depending friction seat wall surrounding the opening in the annular top of the can, of a friction cover having an annular friction seat wall fitting within the annular friction seat wall of the can top and provided with an outwardly projecting flange having an outer folded rim extending over and fitting against the said outer annular raised shoulder on the can top to serve as a stop to limit the extent to which the said friction can or cover 50 may be forced into the annular top of the can and to exclude dirt or other materials from the upper surface of the can top, said can top having also an inner annular shoulder flushed with its outer annular shoulder and an annular channel between said inner and outer annular shoulders, said annular top and cover contacting only at their interengaging friction seat walls and at their outer annular shoulders substantially as specified. 55

3. In a friction top can, the combination with an annular can top having inner and outer annular raised shoulders with an annular channel between said shoulders, and a depending friction seat wall surrounding the 60 opening in said top, of a friction cover having an annular friction seat wall fitting within said friction seat wall of the can top and an outwardly projecting flange extending over and engaging the outer annular shoulder of the can top to limit the extent to which the cap or cover may be forced into the can top, said annular top and cover contacting only at their interengaging friction seat walls and at their outer annular shoulders substantially 65 as specified. 70

4. In a friction top can, the combination with an annular can top having inner and outer raised annular shoulders and a depending friction seat wall surrounding the opening in said top, of a friction cover having an annular friction seat wall and an inner annular shoulder and an outwardly projecting rim provided with a marginal fold and extending over and engaging the outer annular shoulder of the can top to limit the extent to which the cap or cover may be forced into the can top, said can top having an annular channel between its inner and outer annular shoulders, and said friction cover having an annular 75 channel between the outer marginal fold of its rim and its inner annular shoulder, said annular top and cover contacting only at their interengaging friction seat walls and at their outer annular shoulders substantially as 80 specified. 85
